SHOULDER STRAP FOR ACCORDIONS AND
OTHER MUSICAL INSTRUMENTSHerman Petersen, Lynbrook, N. Y., assignor to
M. Hohner, Inc., New York, N. Y., a corpora-
tion of New York

Application January 13, 1939, Serial No. 250,682

6 Claims. (Cl. 84—376)

My invention relates to a new and improved shoulder strap for accordions or other musical instruments.

One of the objects of the invention is to pro-
vide a construction whereby the shoulder straps
will be caused to lie substantially flat against
the accordion when said shoulder straps are not
being used.

Another object is to provide spring means
which will automatically contract the shoulder
straps when they are not in use, so that said
straps will then lie snugly against the instru-
ment.

Another object is to provide a simple and
reliable construction which can be readily ap-
plied to accordions of various sizes, shapes and
styles.

Other objects of my invention will be set forth
in the following description and drawings which
illustrate preferred embodiments thereof, it being
understood that the above statement of the ob-
jects of my invention is intended generally to
explain same without limiting it in any manner.

Fig. 1 is a front elevation showing a part of an
accordion to which the improvement has been
applied. In this view the shoulder straps are
shown in the taut or contracted position.

Fig. 2 is a sectional view on the line 2—2 of
Fig. 1. The broken-line position of the shoulder
strap illustrates how the same is extended into
operative position.

Fig. 3 is a sectional view on the line 3—3 of
Fig. 1.

Fig. 4 is a detail view generally similar to Fig.
1 and showing the shoulder straps in their ex-
tended or operative position.

Fig. 5 is a rear elevation showing a modifica-
tion of the invention, the shoulder straps being
shown in their extended and operative position.

Fig. 6 is a view similar to Fig. 5 showing the
shoulder straps in their taut or inoperative
position.

Fig. 7 is an elevation partially in section, on
the line 7—7 of Fig. 6.

The invention is shown as applied to a con-
ventional accordion A, having the usual key-
board 1. The instrument is provided with two
shoulder straps 2 and 3. The shoulder strap 2
is preferably slightly longer than the shoulder
strap 3. For convenience the invention is de-
scribed with reference to the vertical position
of the accordion which is shown in Figs. 1 and 2.
As shown in Fig. 2 the upper end of the shoulder
strap 2 is connected by means of rivets or other
suitable fastening means 5, to a flexible end-strap

4. Said end-strap is connected by means of riv-
ets 6 to the wall of the instrument. The upper
end of the shoulder strap 3 is similarly con-
nected to the end-strap 4, directly adjacent the
corresponding upper end of the shoulder strap 2. 5

The shoulder straps 2 and 3 pass around and
contact with a turnable roll 7, which has a divid-
ing flange 8.

Referring to Fig. 2, a spiral tension spring
10 is located in a casing 9. Part of the repre-
sentation of the casing 9 has been omitted in
Fig. 1. This casing encloses the spring 10, save
that the outer end of the spring 10 extends
through a suitable opening in said casing 9. The
outer end of the spring 10 is connected by a 15
member 13 to the adjacent end of the shoulder
strap 2. The member 13 may be a rivet or a
pivot pin. The shank of the fastening member
13 is located slidably in the slot 12 of a link 11.
Said slot 12 is closed at both ends thereof. The 20
link 11 is pivotally connected by means of a
member 14 to the lower end of the shoulder strap
3.

When the shoulder straps are not used, the
tension of the spiral spring 10 pulls the shoulder 25
strap 2 taut against the wall of the instrument,
as indicated in full lines in Fig. 2. The pull of
the tension spring 10 is transmitted to the ad-
jacent end of the strap 3, through the link 11
and the shank of the member 13 which then 30
abuts the upper closed end-wall of the slot 12.
The strap 3 is therefore also pulled taut against
the wall of the instrument. When a pull is
exerted upon the shoulder straps, the tension
spring 10 is extended as indicated in Fig. 4 and 35
the lower ends of the shoulder straps 2 and 3
are moved to the position shown in Fig. 4, a
little above the bottom wall of the instrument.
The link 11 is then turned from the inclined
position shown in Fig. 1 and the bodies of the 40
straps are extended relative to the casing of the
accordion, until said bodies are in operative
position, in which the shoulder of the musician
can be inserted between the bodies of the shoulder
straps and the casing of the accordion. The ten- 45
sion spring 10 constitutes pull-means which nor-
mally holds the straps in the full-line position
indicated in Fig. 2, in which said straps are taut
and the bodies of said straps substantially abut
a portion of the casing of the accordion. The 50
straps embrace a portion of the wall of the
accordion.

In the embodiment shown in Fig. 5, one end
of each of the straps 2 and 3 is connected by
rivets 17 to a flexible end-strap 15, which is con- 55

which said intermediate portion is spaced away from said casing when said movable end of the shoulder strap is moved relative to the accordion in a predetermined direction, pull means extending outside of the casing and connected to said movable end of the shoulder strap and adapted to pull said movable end in a direction which is opposite to said predetermined direction until the shoulder strap is substantially taut, the intermediate portion of the shoulder strap abutting and embracing the adjacent portion of the casing when said strap is taut.

6. An accordion having a casing, a shoulder strap having an intermediate portion and having ends which are connected to said casing, com-

pression spring means mounted on said casing, at least one end of said shoulder strap being movably connected to said compression spring, said shoulder strap embracing a portion of said casing, said springs means normally holding the associated movable end of the shoulder strap in a position in which the intermediate portion of the shoulder strap embraces and substantially abuts the associated portion of the casing, said intermediate portion being movable away from said casing when said movable end is moved against the force of said spring means so that the body of the shoulder strap is then spaced from said casing.
